UNITED STATES PATENT OFFICE.

HERBERT MANSELL HARDY, OF UNLEY, SOUTH AUSTRALIA, AUSTRALIA.

SASH-CORD FASTENER.

No. 923,168.

Specification of Letters Patent.

Patented June 1, 1909.

Application filed January 21, 1908. Serial No. 411,900.

To all whom it may concern:

Be it known that I, HERBERT MANSELL HARDY, a subject of the King of Great Britain, residing at Miller street, Unley, in the 5 State of South Australia, Commonwealth of Australia, accountant, have invented a Sash-Cord Fastener, of which the following is a specification.

My invention relates to an improved 10 means for securing sash cords, and constructional details connected therewith, the object of the same being to provide a means whereby sash cords can be readily fitted on to the window sash without necessitating the 15 removal of the sash from its frame.

The invention also provides means whereby the sash weights are rendered more readily accessible for attachment to a new cord after the old cord has been broken.

20 I will now proceed to describe my invention by aid of the accompanying illustrative drawings, in which—

Figure 1. is a perspective side elevation of the sash, showing clips for securing the cord. 25 Fig. 2. is a section on line 2—2 of Fig. 1. Fig. 3. is a side view. Fig. 4. a front view, and Fig. 5 a plan view of the carrier and clip.

In each of the drawings similar letters of 30 reference are used to denote similar or corresponding parts wherever they occur.

An ordinary sliding sash is shown at *a* and works vertically in the window grooves in the well known manner. A recess is 35 formed in the sash at *b* as has hitherto been the custom for the accommodation of the sash cord, but instead of merely placing the cord thereon a slide carrier *c* is permanently secured within the recess.

40 The slide carrier consists of a body part the upper portion of which is bent over at *d* the said portion *d* being arranged to lie horizontally in a recess on the upper portion of the sash, the bend at the top being 45 of a rounded nature so as not to damage the material by bending it too abruptly at right angles. This slide carrier is formed with grooved edges *e* for the reception of the sliding clip *f* which is inserted in the vertical part of the slide carrier, and for the reception of the slide cover *g* which works in the horizontal portion of the slide carrier on the top of the sash. The upper portion 50 of the slide clip is bent at right angles at *h*

the arrangement being such that the bent 55 portion lies adjacent to the upper portion of the slide carrier when the slide clip is in its secured position as shown in Fig. 3 of the drawings. The slide clip is further characterized by notched portions or projections *j* 60 of which there may be several arranged upon the clip, their construction being such as to enable them to be bent into and grip upon the sash cord *k* which said sash cord passes over a pulley at the top of the window frame in the usual well known manner and is attached at its opposite end to a sash balance weight.

The method of securing the cord by means of the notched portion or projection *j* will 70 be readily understood from the drawings. The method of securing the slide clip consists in simply inserting the same within the vertical part of the slide carrier and pressing it downward until the portion *h* 75 of the clip comes to rest upon the portion *d* of the carrier. As soon as this position is reached the slide cover *g* is drawn forward in the direction of the arrow shown in Fig. 3 until it passes over the portion *h* of the 80 slide clip thereby securely holding the same and preventing its removal from the carrier. In event of the sash cord becoming broken it is only necessary to press the slide cover *g* 85 backward in the opposite direction to that shown by the arrow when the slide clip may then be readily removed from the carrier and the end of the old cord is extracted therefrom and replaced by a new one.

Any convenient class of metal may be 90 used for the construction of my invention the size and shape of which may be varied within reasonable limits and the contour and form of the notched portion *j* can also be varied, it being desirable however to form 95 plain projecting portions thereon as shown in the illustration which are readily accessible to be operated upon by ordinary pliers.

Having now particularly described and ascertained the nature of my said invention 100 and in what manner the same is to be performed I declare that what I claim is:—

A sash cord fastener comprising a carrier having grooved edges, a portion of said carrier being bent at right angles and being 105 adapted to be seated in a groove in the window sash, a slide having its edges engaging the grooved side of the carrier and

having a bent portion adapted to engage with the bent portion of the carrier, a sliding cover operating in said bent portion of the carrier and adapted to engage with the bent portion of the slide to hold the same in place, and means on the slide for engaging the sash cord.

In testimony whereof I affix my signature in presence of two witnesses.

HERBERT MANSELL HARDY.
